Primary Examiner — Mark A Goodwin*Assistant Examiner* — Adam C Mager*(74) Attorney, Agent, or Firm* — Buchanan Ingersoll & Rooney PC**(57) CLAIM**

The ornamental design for a wheel for motor vehicle, as shown and described.

DESCRIPTION

FIG. 1 is a perspective view of a wheel for motor vehicle; FIG. 2 is a left side view thereof; and, FIG. 3 is a top view thereof.

The broken lines illustrate portions of the wheel for motor vehicle in which the design is embodied that form no part of the claimed design.
